SHIP LAUNCHING DEVICE

James B. Hall, Nashville, Tenn.

Application July 24, 1944, Serial No. 544,281

12 Claims.

(Cl. 61—67)

This invention is a ship launching device, particularly relating to means for holding a ship on the ways during construction, and for releasing it for launching. The invention is particularly concerned with a quick release means for holding the ship on the ways for side-wise launching, but the invention is not restricted to use for side-wise launching. It may be used also on marine rail-ways.

At the present time the cradle holding the ship prior to side-wise launching is provided with a number of clevises, depending on the length and tonnage of the ship. Usually these clevises are about 25 or 30 feet apart. It has been customary to tie or secure these clevises to suitable cross beams on the ways by manila rope about 2 or 2½ inches in diameter, and when the ship is ready to launch, a man provided with an axe at each clevis, at a given signal, cuts this rope for allowing the ship to slide down the ways. The cost of these ropes for launching a medium size ship is in the neighborhood of \$109 or \$125.

The object of this invention is to provide a series of manually releasable locking devices for holding the several clevises so that at a given signal a man at each clevis throws a lever, thereby releasing the ship for launching and eliminating the necessity of using rope.

More particularly, the invention comprises, for each clevis, an angled pad strongly secured in position to the ways. Cooperating with the angled pad is a similarly angled slide, which is detachably clamped to the clevis. The pad and slide are similarly shaped so that their angled surfaces form bearing surfaces which fit snugly against each other, and the angle of this bearing surface is at an angle with respect to the direction of pull exerted by the ship on the clevis and on the slide. Therefore, when the pad and slide are held clamped together, the pull of the clevis is taken up by the bearing surfaces and the ship is held. However, if the slide is released, the slide rides up on its bearing surface, due to the pull of the ship, and the clevis is thereby released.

The slide is clamped against the pad, with the angled bearing surfaces of the slide and pad held firmly in engagement, by means of a locking lever, the mechanical advantage of which is sufficient to hold the pad and slide in locking position against the pull of the ship. These locking levers are normally secured by a padlock in locking position against unauthorized use.

When the ship is to be launched, the levers are unlocked and, at a given signal, a workman at each lever throws the lever to unlock his particular clevis, and the ship is thereby released for launching.

The invention will be further described in connection with the accompanying drawing, illustrating one embodiment of the invention, more or less diagrammatically, in which:

Figure 1 is a side view of the ship launching device of the present invention; and

Figure 2 is a plan view of the same.

Referring now to these figures, 2 indicates the usual inclined ways, supporting the slidable platform, comprising horizontal side beams 4 and inclined side beams 6, slidable on ways 2; this platform carries the usual cradle 7 for supporting the ship 8 to be launched.

10 Side beams 4 of the ways are usually provided with anchor plates 12 secured thereto by bolts 14 and with inwardly extending, heavy, strong pivots 16 which engage with the ends 18 of clevis 20. The parts so far described are already in use today.

Coming now to the securing device of the present invention, a pad 22 is secured to the usual heavy crossbeam 24 at the end of the ways. This pad 22 is a heavy metal plate about an inch or two thick, and it is secured to the beam 24 in any suitable way, as by a plate 26 which is bolted to the beam by a bolt 28, the upper edge of plate 26 being welded at 30 to the underside of the pad 22.

Coming now to the most important feature of 25 the present invention, the pad 22 is provided with an angled portion 32 having an upper bearing face 34.

Cooperating with the pad 22 is a slide 36, the body portion of which rests on pad 22, the slide 30 being provided with an angled portion 38 provided with an angled bearing surface 34'.

Bearing surfaces 34 and 34' are at the same angle and are normally in contact. The angle of these bearing surfaces is at an angle to the pull 35 exerted by clevis 20. The angle of the bearing surfaces is about 45° with respect to the surfaces of the body portions of the slide and pad. However, this angle can be varied as desired; if heavier ships are to be handled, the angle may 40 be increased.

The slide 36 is secured in any suitable way to clevis 20, as by the U-member 39, engaging with the clevis, and a bolt 40, passing through the ends of 45 39 and through a hole in the end of slide 36, the bolt hole being reinforced by heavy washers 41 welded in place.

In order to hold the slide in locking position on the pad as shown in Fig. 1, a lever 42 is provided, pivoted at 44 to the pad, the lower part 43 of the lever straddling the upper ends of the pad and slide. The lever carries a transversely extending bearing roller 46, journaled on shaft 47, to arms 43 which bears against the outer or upper surface 46' of the slide, near the angled portion 38 thereof, so that when the lever is in the position shown in Fig. 1, the pad and slide are locked together, and so the ship is held on the ways. The lever 42 is normally held in this position by a chain 48 secured by padlock 50 against unauthorized use.

In order to prevent the clevis from dropping

down and dragging, after it has been released in launching the ship, a supporting bar or rod 52 may be positioned underneath it, supported by the side beams 2. In order to prevent any possible sidewise movement of the slide 36, chains or the like 54 may be positioned between respective outer edges of the slide 36 and the inner edges of the side beam 2.

When it is desired to launch the ship, a workman is stationed at each lever 42 and at a given signal swings the lever 42 to the right, thereby releasing the several slides 36, whereupon the pull exerted by the clevis causes the two angled surfaces 34 and 38 to act as cooperating cams, causing the angled end 38 of the slide to ride up on the bearing surface 34, thereby releasing the slide and releasing the clevis and allowing the ship to slide down the ways 2.

While the invention has been illustrated in some detail, it should be understood that the invention is not to be limited to the precise details shown, but may be carried out in other ways.

I claim as my invention:

1. A ship launching device, comprising in combination an angled pad fixed in position at an angle with respect to the pull exerted by the ship, an angled slide connected to and movable with the ship to be launched, and means for releasably clamping said slide to said pad with their angled portions in engagement.

2. A ship launching device, comprising in combination a pad, provided with a bearing face extending at an angle with respect to the pull exerted by the ship as it is held on the ways, a slide, connected to the ship to be launched, provided with an angled bearing face adapted to fit against the bearing face on the pad whereby the said angled bearing faces of the slide and the pad form cooperating cam surfaces, and means for releasably clamping said bearing faces into engagement.

3. A ship launching device, comprising in combination an angled pad fixed in position at an angle with respect to the pull exerted by the ship, an angled slide connected to and movable with the ship to be launched, and a locking lever bearing against an outer portion of said slide, for releasably clamping said slide against said pad with their angled portions in engagement.

4. A ship launching device, comprising in combination a pad provided with a bearing face extending at an angle with respect to the pull exerted by the ship as it is held on the ways, a slide, connected to the ship to be launched, provided with a bearing face adapted to fit against the bearing face on the pad, and a locking lever bearing against an outer portion of said slide, for releasably clamping the slide to the pad, with their angled bearing faces in engagement.

5. A ship launching device, comprising in combination an angled pad fixed in position at an angle with respect to the pull exerted by the ship, an angled slide connected to and movable with the ship to be launched, and a locking lever pivoted to the pad and bearing against an outer portion of said slide, for releasably holding the pad and slide in engagement.

6. A ship launching device, comprising in combination a pad, provided with a bearing face extending at an angle with respect to the pull exerted by the ship as it is held on the ways, a slide, connected to the ship to be launched, provided with a bearing face adapted to fit against the bearing face on the pad, and a locking lever

pivoted to the pad and bearing against an outer portion of the slide, adjacent the angled bearing face thereof, for releasably holding the pad and slide clamped together, with their angled bearing faces in engagement.

7. A ship launching device, comprising in combination an angled pad fixed in position at an angle with respect to the pull exerted by the ship, an angled slide connected to and movable with the ship to be launched, means for releasably clamping said slide to said pad with their angled portions in engagement and means for securing said clamping means against unauthorized use.

8. A ship launching device, comprising in combination a pad provided with a bearing face extending at an angle with respect to the pull exerted by the ship as it is held on the ways, a slide, connected to the ship to be launched, provided with a bearing face adapted to fit against the bearing face on the pad, means for releasably clamping said bearing faces into engagement and key controlled means for securing said clamping means against unauthorized use.

9. A ship launching device, comprising in combination a pad provided with a bearing face extending at an angle with respect to the pull exerted by the ship as it is held on the ways, a slide, connected to the ship to be launched, provided with a bearing face adapted to fit against the bearing face on the pad, a locking lever pivoted to the pad and bearing against an outer portion of the slide, adjacent the angled bearing face thereof, for releasably holding the pad and slide clamped together, with their angled bearing faces in engagement and means for securing said locking lever against unauthorized use.

10. A ship launching device, comprising in combination, a clevis secured to the cradle supporting the ship to be launched; a pad fixed in position, a slide connected to the clevis and slidable on said pad, said pad and slide being provided with contacting angled bearing surfaces, the angle of said contacting surfaces being at an angle with respect to the direction of pull exerted by the clevis on said slide, and means for releasably clamping said pad and slide in engagement, with their angled bearing surfaces in contact.

11. A ship launching device, comprising in combination, a clevis secured to the cradle supporting the ship to be launched, a pad fixed in position, a slide, connected to the clevis and slidable on said pad, said pad and slide being provided with contacting angled bearing surfaces, the angle of said contacting surfaces being at an angle with respect to the direction of pull exerted by the clevis on said slide, and a manually operated lever for releasably holding said pad and slide in engagement, with their angled bearing surfaces in contact.

12. A ship launching device, comprising in combination, a clevis secured to the cradle supporting the ship to be launched, a pad fixed in position, a slide, connected to the clevis and slidable on said pad, said pad and slide being provided with contacting angled bearing surfaces, the angle of said contacting surfaces being at an angle with respect to the direction of pull exerted by the clevis on said slide, and a lever, pivoted to the pad and engageable with the outside of the slide adjacent the end having the bearing surface, for releasably clamping said pad and slide in engagement, with their angled bearing surfaces in contact.
